UNITED STATES PATENT OFFICE.

SAMUEL CLYDE KYLE, OF NEW YORK, N. Y.

DESIGN FOR A SMOKER'S STAND.

Application filed January 6, 1928. Serial No. 24,762. Term of patent 14 years.

To all whom it may concern:

Be it known that I, SAMUEL CLYDE KYLE, a citizen of the United States, residing in the city, county, and State of New York, have invented a new, original, and ornamental Design for a Smoker's Stand, of which the following is a specification, reference being had to the accompanying drawing, forming a part thereof.

In the drawings:

The salient feature of the invention consists in mounting the ash tray holding arms upon a standard carrying at the top thereof a wheel in simulation of the steering wheel of a maritime vessel.

I claim:

The ornamental design for a smoker's stand substantially as shown and described.

SAMUEL CLYDE KYLE.
